[57] CLAIM

The ornamental design for a balcony tray, substantially as shown and described.

DESCRIPTION

FIG. 1 is a perspective view of one embodiment of a balcony tray embodying my design as seen from the back, one side and top thereof;

FIG. 2 is another perspective view of such one embodiment as seen from the front, other side and bottom thereof;

FIG. 3 is a perspective view of a second embodiment of a balcony tray embodying my design as seen from the back, one side and top thereof; and

FIG. 4 is another perspective view of the second embodiment as seen from the front, other side and top thereof.

The broken lines indicating a balcony railing fragment in FIGS. 1 and 3 have been shown for illustrative purposes only.
